US00D401629S

United States Patent [19]

Wing

[11] Patent Number: Des. 401,629
 [45] Date of Patent: **Nov. 24, 1998

[54] POWER GRIP GAME

[75] Inventor: Yu Wah Wing, Tsuen Wan, Hong Kong

[73] Assignee: Tiger Electronics, Inc., Vernon Hills, Ill.

[**] Term: 14 Years

[21] Appl. No.: 49,037

[22] Filed: Jan. 16, 1996

[51] LOC (6) Cl. 21-01

[52] U.S. Cl. D21/13

[58] Field of Search D21/13, 1, 48; 273/148 B; 463/30-35, 43-47; D14/125, 126
